UNITED STATES PATENT OFFICE.

GEORGE WHITE, OF ROCK ISLAND, ILLINOIS.

LIGHT.

1,359,136.

Specification of Letters Patent. Patented Nov. 16, 1920.

Application filed May 26, 1919. Serial No. 299,742.

To all whom it may concern:

Be it known that I, GEORGE WHITE, a citizen of the United States, residing at Rock Island, in the county of Rock Island and State of Illinois, have invented certain new and useful Improvements in Lights, of which the following is a specification, reference being had to the accompanying drawings.

10 This invention relates to certain improvements in lights, and it is an object of the invention to provide a novel and improved device of this general character especially designed and adapted for use in connection with automobile curtains or the like.

It is also an object of the invention to provide a novel and improved light which is of little weight so that the same may be maintained in operative position without strain upon the securing means therefor and without damaging the curtain or other object with which it is engaged.

Another object of the invention is to provide a novel and improved device of this general character formed of a transparent sheeting, such as celluloid, pyrolene, or the like, and which has its marginal portions provided with bevels so that the sheeting closely simulates the appearance of plate 30 glass.

An additional object of the invention is to provide a light of this character comprising two overlying sheetings of transparent material, such as celluloid, or the like, and 35 wherein one of said sheetings has its marginal portions provided with bevels while the second sheet operates to maintain said bevels.

The invention consists in the details of 40 construction and in the combination and arrangement of the several parts of my improved light whereby certain important advantages are attained and the device rendered simpler, less expensive and otherwise 45 more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation of a light construction in accordance with an embodiment of my invention.

Fig. 2 is a fragmentary sectional view

taken substantially on the line 5—5 of Fig. 1, and

Fig. 3 is a fragmentary view in perspective of a marginal portion of my improved light as disclosed in Figs. 1 and 2.

As disclosed in the accompanying drawings, C denotes a curtain having a window opening W therein and over which is disposed a light L constructed in accordance with my invention.

The light L includes a transparent sheeting 1 of celluloid, pyrolene, or the like, and the marginal portions of the sheeting are provided with the bevels 2 pressed or otherwise formed. The outer marginal portions of the bevels are provided with sufficient extension 3 whereby the light may be secured in working position.

As disclosed in the accompanying drawings, the sheeting 1 is maintained in working position by the stitching 4 directed through said extension 3 and through the curtain C. It will be understood, however, that fastening means other than the stitching may be employed in accordance with the preference of the user.

It is also preferred that, in order to give a finished effect, strips 5 be secured to the curtain C and overlie the extension 3, the stitching 4 or other fastening means being also directed through the strips 5.

As before stated, my improved light is particularly adapted for use in connection with curtains for automobiles or other vehicles and the same closely simulates the esthetic effect of bevel plate glass, but the particular advantage of the use of my improved light is the fact that it is of little weight, so that damaging of the curtain by the light and of the fastening means for the light is substantially entirely eliminated.

Each of the extensions 3 at a point intermediate the inner or lower edge of the adjacent bevel 2 and the adjacent marginal portion of the window opening W is provided therealong with the corrugations 7.

The corrugations 7 act as a release for the tension caused by the pulling of the curtain C when in motion and also by the additional pulling of the curtain C after it becomes weather-worn and shrinks. The shrinking of the curtains causes an unusual strain on the curtain light now generally employed, resulting in the same breaking or pulling apart. The yielding action afforded by the corrugations 7 will materially obviate

this decided disadvantage. The bevel 2' to a certain extent compensates for this action but not to the same advantage offered by the corrugations 7.

5 It is also to be understood that my improved light may be of any configuration desired and as may be occasioned by the requirements of practice.

10 It is also to be stated that while my improved light is primarily adapted for use in connection with curtains for automobiles or other vehicles, it can be readily employed for other purposes as a substitute for glass lights or panels.

15 When I hereinbefore refer to the panels 2, it is to be understood that I do not intend to limit myself to such bevels being straight in cross section as the same may be disposed on a curvature, yet this latter arrangement 20 is believed to fairly fall within the general meaning of the word bevel.

From the foregoing description, it is thought to be obvious that a light constructed in accordance with my invention is

25 particularly well adapted for use by reason of the convenience and facility with which it may be assembled and operated, and it will also be obvious that my invention is susceptible of some change and modification 30 without departing from the principles and spirit thereof and for this reason I do not wish to be understood as limiting myself to the precise arrangement and formation of the several parts herein shown in 35 carrying out my invention in practice except as hereinafter claimed.

I claim:

1. As a new article of manufacture, a light for a vehicle curtain formed from a trans-

parent sheeting and having its marginal 40 portion beveled, said beveled portion having sufficient extension to afford securing means, said extension having an expansible corrugation extending therealong, said corrugation being positioned immediately adjacent 45 the bevel.

2. As a new article of manufacture, a light for a vehicle curtain formed from a transparent sheeting and having its marginal portion beveled, said beveled portion having 50 sufficient extension to afford securing means, said extension having an expansible corrugation extending therealong.

3. As a new article of manufacture, a light for a vehicle curtain formed from a transparent sheeting and having its entire marginal portion angularly directed to afford a bevel, the outer portion of said bevel being continued by an extension to afford securing means, said extension having an expansible 60 corrugation to permit contraction or expansion of the light.

4. As a new article of manufacture, a light for a vehicle curtain formed from a transparent sheet, said sheet having an expansible 65 corrugation extending therealong inwardly of its margin.

5. As a new article of manufacture, a light for a vehicle curtain formed from a flexible transparent sheeting and an expansible corrugation extending around the marginal 70 portion of the sheeting.

In testimony whereof I hereunto affix my signature in the presence of two witnesses,

GEORGE WHITE.
